UNITED STATES PATENT OFFICE.

HOOKER I. COGGESHALL, OF WORTENDYKE, NEW JERSEY.

STEAM-JET FLUE-CLEANER.

SPECIFICATION forming part of Letters Patent No. 656,945, dated August 26, 1900.

Application filed January 11, 1900. Serial No. 1,142. (No model.)

To all whom it may concern:

Be it known that I, HOOKER I. COGGESHALL, a citizen of the United States, and a resident of Wortendyke, in the county of Bergen and State of New Jersey, have invented a new and Improved Steam-Jet Flue-Cleaner, of which the following is a full, clear, and exact description.

This invention relates to a class of boiler tube or flue cleaners which project a forcible jet of steam into one end of the flue to be cleaned and by impact of the current of steam loosen and remove scale and dirt that clog the flue.

The object of my invention is to provide novel details of construction for a device of the indicated class which will afford a superior jet-flue cleaner, which will be very effective in operation, and that may be produced at moderate cost.

The invention consists in the novel features of construction and combination of parts, as is herein-after described, and defined in the appended claims.

Reference is to be had to the accompanying drawings, forming a part of this specification, in which similar characters of reference indicate corresponding parts in all the figures.

Figure 1 is a side view of the improved flue-cleaner applied to a portion of a flue indicated by dotted lines. Fig. 2 is a longitudinal sectional view taken substantially on the line 2-2 in Fig. 1, and Fig. 3 is an end view of the device seen in the direction of the arrow x in Fig. 2.

The improvement as represented comprises a conical shell or body 4, which is partly closed at the larger end by an annular wall 5, from which centrally projects a collar 6, internally threaded for screwed engagement therewith of one end of the blower-pipe 7. From the smaller end of the coniform body 4 extends a nozzle 8 in cylindrical form, the bore 9 of which is of a proper diameter to adapt said nozzle for effective service. Preferably the nozzle 8 is so reduced in the diameter of its bore that the diameter of the blower-pipe exceeds it, which gives great force to the steam-jet issuing from the nozzle and adapts the flue-cleaner for highly-efficient service, while using but a small amount of steam.

Another feature of invention, as shown,

comprises a series of similar wings 10, projected from the outer surface of the coniform body 4, these equally-spaced wings twisting spirally in the same direction, so that they are disposed substantially parallel with each other, and represent portions of coarse-pitched screw-threads, as clearly indicated in Figs. 1 and 3.

The blower-pipe 7 (shown partially) in complete form is adapted for flexible connection with a source of high-pressure-steam supply, as is common for such devices, and of course means to control the influx of steam into the blower-pipe is provided therefor.

In operation the hollow head 4 on the end of the pipe 7 is introduced within the end of one of a plurality of flues or tubes A in a boiler that need cleaning. Steam of high pressure is passed through the blower-pipe 7 into the coniform head 4 and highly heats said head, the wall of which is comparatively thin to adapt it to become heated quickly, which is very essential for the proper operation of the improved flue-cleaner. It will be seen in Fig. 1 that the wings 10 prevent the complete entrance of the hollow head 4 within the flue A, and the contact of said wings with the tube or flue will serve to center the head 4 and nozzle 8 therein. The pressure of steam that passes into and through the blower-head and nozzle thereon will cause a current of air to be drawn between the wings 10 over the coniform head or body 4 and mingled with the steam-jet, this induction of atmospheric air being effected by the partial vacuum produced in the flue by the rapid current of steam entering the same. As the forcible air-current mingles with the steam-jet so as to cause the air and steam currents to twist in the same direction, these combined jets coact with force upon the loose scale and soot that clog the flue, blowing such obstructions out of the opposite end of the flue.

Having thus described my invention, I claim as new and desire to secure by Letters Patent—

1. The combination with the coniform blower-head, and a plurality of spirally-disposed and equally-spaced wings thereon, of a blower-pipe at the larger end of the coniform blower-head, and a cylindrical nozzle projected from the smaller end of said blower-

head, having less internal diameter than the blower-pipe for the purpose set forth.

2. The combination with a blower-pipe, and a hollow coniform blower-head securable thereon at the larger end of said blower-head, the side wall of the latter being thin to adapt it to heat quickly when steam passes therethrough, of a plurality of spirally-disposed wings on the exterior of the blower-head equally spaced apart and trending in the same direction, and a jet-nozzle extending from the

smaller end of the blower-head, having less internal diameter than that of the blower-pipe, for the purpose specified.

In testimony whereof I have signed my name to this specification in the presence of two subscribing witnesses.

HOOKER I. COGGESHALL.
